UNITED STATES PATENT OFFICE.

EDWIN N. CHANDLER, OF BRAINTREE, MASSACHUSETTS, ASSIGNOR TO BOSTON LAST COMPANY, OF BOSTON, MASSACHUSETTS, A CORPORATION OF MAINE.

ELECTRICALLY-HEATED SHOE-IRON.

1,228,180.

Specification of Letters Patent. Patented May 29, 1917.

Application filed October 7, 1914. Serial No. 865,471.

To all whom it may concern:

Be it known that I, EDWIN N. CHANDLER, a citizen of the United States, and resident of Braintree, county of Norfolk, State of 5 Massachusetts, have invented an Improvement in Electrically-Heated Shoe-Irons, of which the following description, in connection with the accompanying drawings, is a specification, like letters on the drawings 10 representing like parts.

My present invention is a hand ironing tool, especially intended for use on boots and shoes, and provided with electrical heating means. This iron is of novel form, designed 15 particularly to enable the operator to smooth and iron out the boot or shoe upper around the varying contour, concavities, crevices, and the like, which are present in the outer surface of a shoe. It has heretofore been particularly difficult to reach the 20 hollow of the shank or arch of the shoe, and also the crease between the shoe upper and the projecting edge of the welt or sole, and my present invention is intended to provide 25 a tool which will be capable of effective work on those parts of a shoe, as well as on the rest of the surface. Such an iron is of great value to lasters, in smoothing out 30 the wrinkles in a shoe vamp or upper after it is pulled over and lasted. It is also of use in the manufacture of turned shoes, after the shoe has been turned and is being 35 fitted on a follower, it then being desirable to smooth out and iron the upper to remove wrinkles and fit the leather to the contour of 40 the new last on which it has been positioned. A further important object is the provision of electrical heating means which enables the entire iron to be evenly heated, and 45 maintained at just the right degree of heat for the best work, not affording too great heat to injure the leather and not permitting the iron to get cold during use. This feature is of special importance as heretofore 50 such shoe irons have simply been thrust into a steam or gas heater and withdrawn therefrom when needed for use, the iron being apt to be overheated and necessarily rapidly cooling during use so that a uniform action was impossible.

In addition to the novel form of heating iron, I have provided a construction permit-

ting a removable heating unit to be employed so that the same may be readily renewed at any time, and furthermore have 55 devised a handle which will automatically operate to hold the heating unit in the iron and to conduct the wires supplying electrical current out of the way of the operator. The present invention also is specially applicable, both in the form of tool and the handle construction, to provide an improved 60 electrically heated seam-rubbing machine.

Referring to the drawings, illustrating 65 preferred embodiments of the invention.

Figure 1 is a side view of the ironing tool, showing its application to the welt crease of 70 a shoe;

Fig. 2 is a view showing the application 75 to the shank of a shoe;

Fig. 3 is a cross sectional view on the line 3—3 of Fig. 1;

Fig. 4 is a cross sectional view on the line 4—4 of Fig. 1, showing the form, in 80 cross section, of the tool.

As shown in the drawings, the ironing tool comprises a metallic working portion 1 and a handle 2, the latter being usually formed of wood, and being preferably 85 formed hollow. The tool portion 1 is of substantially triangular form in cross section, having a flat base 3 which is of special value for ironing out and smoothing wrinkles in some parts of the shoe, and also to provide a straight smooth bearing for the 90 tool when the operator runs it along the welt crease of the shoe. This operation is illustrated in Fig. 1, a shoe sole 4 and shoe upper 5 being illustrated in dotted lines with the smoothing iron applied to the welt 95 crease. The other sides of the tool are partly straight and are united by curved section 6, which enables the tool to be readily manipulated from one point to another about the shoe, and also to get in the 100 creases around the instep portion. The ridge of the curved part 6 is formed substantially parallel with the flat base 3, for a considerable distance, and then tapers at 7 until it unites with the straight base 3, this particular construction facilitating the operation of the ironing tool in the shank of the shoe, as illustrated in Fig. 2. It has heretofore been extremely difficult to smooth

out the wrinkles in the shank under the arch, as at this point wrinkles are peculiarly apt to form during the lasting, and the value of the iron for this work is of special importance. This exterior contour of my improved iron is of novel form and being of particular utility I wish to claim the same broadly. To provide a uniform heat capable of electrical supply, I form the iron 5 hollow with a recess 8 of appropriate diameter and depth to receive an electrical heating unit 9, said unit being preferably removable and united with supply wires 10. To facilitate the application of the heating unit 10 to the iron, I form the handle 2 hollow, as above stated, and adapt the wooden portion 2 of the handle to fit upon a tubular sleeve 11, said sleeve having one end threaded at 15 12 and engaged with the threads of a nut 13 embedded within the handle. The other end of the tube 11 is split and flattened and formed into side flanges 14 which are substantially in the form shown in Fig. 3, and are perforated to receive bolts 15. The iron 20 1 is formed with oppositely extending lugs 16, each lug being tapped at 17 to receive the threaded ends of bolts 15, said lugs being positioned to coöperate with the flanged ends 14, to be united by the bolts 25 15 as shown in the drawings. Gaskets or washers 18 are also fitted between the lugs 16 and flanges 14 to aid in insulating the head of the tool 1 from the handle 2. I may provide washers 19 and 20 of rubber 30 or the like to hold the wires 10 centrally of the sleeve 11 and the handle 2 yieldingly on the sleeve 11, respectively, these washers also serving as heat insulating devices, in 35 addition to the air space between the heating tool and handle.

It will be noted that the heating unit being removable can be readily detached by removal of the bolts 15 and a new heating unit applied at any time. Also this enables 40 the ironing tool to be shipped long distances without the heating unit being fitted therein and when desired for use, the handle is detached and the heating unit 9 and wires 10 applied thereto by drawing the wires through 45 the handle, the attachment of the bolts 15 serving to hold both the handle and the heating unit in assembled position in the iron, while the supply wires 10 are conducted out of the way of the operator.

50 My invention enabling a uniform degree of heat to be supplied to a hand ironing tool, as well as to a seam rubber, greatly facilitates these operations and enabling them to be performed more quickly and 55 with more satisfactory results than has heretofore been possible. I find that in practical use my electrically heated shoe iron, being light and strong and with the current supply wires led from the end of 60 the handle entirely out of the way, may

be manipulated around each and every portion of the shoe, particularly the arch of the shank and the rand and welt creases, smoothing and ironing all wrinkles by the application of heat and pressure, such pressure being applied as the operator may desire by rubbing, hammering, and burnishing, and repeatedly applied to the same part when necessary. 70

Having described my invention, what I 75 claim as new and desire to secure by Letters Patent is:

1. An electrically heated shoe finishing iron, having a substantially flat surface throughout its entire extent from end to end, one end of said iron being pointed and tapering from a rounded contour above said flat surface, said iron being formed with a recess opening at its other end to receive a removable heating unit, and means 80 to hold a handle to said recessed end in such manner that said handle is insulated from the heat of the iron. 85

2. An electrically heated shoe finishing iron, having a substantially flat surface throughout its entire extent from end to end, said iron having an end face extending upwardly from said flat surface to a rounded contour above said flat surface and being inclined to said flat surface at an acute angle such that the tapered end of said iron can readily be inserted in the welt crease of a shoe, said iron being formed with a recess open at its other end to receive a heating unit, a handle adapted to receive and conduct heat supply wires therethrough and means to unite the handle to said iron adjacent said recess, said uniting means providing heat insulation for said handle. 95

3. An electrically heated shoe finishing iron, adapted to fit within the shank and welt crease of a boot or shoe, having a substantially triangular form in cross section with a rounded angle uniting two sides, said iron at one end tapering downwardly to its bottom edge, said iron being formed with a recess to receive a detachable electric heating unit, a handle having tubular conducting means therein for the supply wires for said heating unit with one end of said tube secured to said handle, and the other end having flanges secured to the heating iron, and heat insulating means between the iron and handle. 100

4. An electrically heated hammering and burnishing tool comprising a body having a cylindrical socket which is open at one end of the body, the opposite end being closed, a portion of said socket wall having a rounded external face capable of use as a hammer head, while another portion of said wall has a flat burnishing face extending from end to end of the body, and a U-shaped burnishing face inclined rela- 115 120 125 130

tively to said flat face and intersecting the latter to form an acute angled U-shaped burnishing edge extending along both sides of the body and across its outer end, and 5 an electrical heating unit removably inserted in said socket.

In testimony whereof, I have signed my

name to this specification, in the presence of two subscribing witnesses.

EDWIN N. CHANDLER.
